J. E. OGDEN.

ADJUSTABLE LINK DOOR.

APPLICATION FILED MAY 6, 1920.

1,378,127.

Patented May 17, 1921.

Inventor
John Edward Ogden
By his Attorney
E. M. Marshall

UNITED STATES PATENT OFFICE.

JOHN EDWARD OGDEN, OF MOUNTAINVILLE, NEW YORK.

ADJUSTABLE-LINK DOOR.

1,378,127.

Specification of Letters Patent. Patented May 17, 1921.

Application filed May 6, 1920. Serial No. 379,221.

To all whom it may concern:

Be it known that I, JOHN EDWARD OGDEN, a citizen of the United States of America, and a resident of Mountainville, county of 5 Orange, and State of New York, have invented certain new and useful Improvements in Adjustable-Link Doors, of which the following is a specification, reference being had to the accompanying drawings, 10 forming a part hereof.

This invention relates to improvements in doors of the type used in warehouses, pier sheds and similar places where large openings are to be covered and where the space 15 through which the doors are moved to open is valuable and limited.

It relates more particularly to doors of which a section at least is suspended by links which swing such section of the door 20 into a substantially horizontal position when it is open. It is common practice to have another section of the door slideable up onto the link suspended section before the latter is moved. Such doors are necessarily heavy 25 and the problem of counter-balancing them becomes quite complex.

The specific object of this invention is to provide links of adjustable length and connections between the link suspended door 30 section and the links which are adjustable in position for the purpose of simplifying the counter-balancing adjustment of the installation.

Incidentally, other advantages are attained by this invention, which will appear 35 in the following specification, in which I will fully describe the invention, the novel features of which will be set forth in appended claims.

40 Referring to the drawings:

Figure 1 is an end elevation of a door of this general character with an embodiment of this invention applied thereto.

Fig. 2 is an elevation of a two-part link 45 of adjustable length.

Figs. 3, 4 and 5 are elevations of parts of links of other constructions, which are also adjustable in length and which may be used in carrying out this invention.

50 Fig. 6 is a sectional plan view of a part of the mechanism shown in Fig. 1, the section being taken on the line 6-6 of the latter figure.

Fig. 7 is a side elevation of an adjustable 55 link pin plate of different construction than that shown in Figs. 1 and 6.

Fig. 8 is a side elevation of another modification of a link pin plate.

Like characters of reference designate corresponding parts in all the figures of the 60 drawings.

10 designates a door-header, 11 an actuating shaft and 12 a counterweight sheave affixed to the shaft. 13 is a link support affixed to the door header in desired position as by bolts 13^A, passing through desired holes 13^B in a flange whereby its position may be adjusted. The side posts of the door opening are designated by 14, and 15 is a guide parallel with these side posts. 70

The upper door section, designated by 20, is of sufficient width to enable it to overlap the opening and rest upon the side posts 14 when it is closed. This upper door section is suspended from the super-structure 75 by a two-part link 21, 22 rotatably connected with the support 13 and by link pin plates 23 with the edges of this door section about mid-way between the top and bottom thereof. These plates project inwardly beyond the side posts 14.

According to this invention, the distance of the pivotal connections between the lower ends of the links and the door posts is adjustable for reasons which will be fully described hereinafter. 85

At the sides of the upper door section are channels 24 which protect the sides and outer edges of this door section and form guides for the reception of the lower door 90 section.

The lower door section 30 has rollers 31 near its lower corners, which run in the guides 15. The vertical edges of the upper part of the lower door section enter the 95 space between the inner surface of the upper door section and the inner flanges of the channels 24.

32 designates one of the hoisting chains or cables of which there are two, located 100 one at each of the opposite sides of the door. These run over the sheaves 12 on the actuating shaft 11 and down to counterweights 33.

Before describing the novel features of 105 the present invention, the operation of doors of this type will be described briefly.

Rotation of the shaft 11 will pull the chains 32 up, and raise the lower door section 30, first up into a position over the upper door section. This will uncover a substantial part of the door opening, enough in 110

fact, to make it usable. Projections, such as those formed by brackets 34 affixed to the lower part of the lower door section limit the movement of this section relative to the upper door section, by coming in contact with the lower edge of the latter.

Continued upward movement of the chains will cause the lower edge of the lower door section to move upwardly, guided by the rollers 31 in the track or guides 15, but this continued upward movement of the lower edge of the lower door section will carry the lower edge of the upper door section with it. The other parts of both door sections, however, will swing inwardly, as permitted by the links 21, 22. This movement may be continued until the door sections reach a horizontal position, or as far as desired.

In closing the door, the rotation of the shaft 11 in the opposite direction will permit the rollers 31 to move downwardly in the guides 15 and this will cause the links to swing back into their initial position until the upper door section comes in contact with the door posts 14 at which time the guides on the upper door section 20 formed by the channels 24 will be in alinement with the guides 15 below said door section, where-by the lower door section 30 may now be lowered until the door opening is completely closed.

To obtain a proper balance of doors of this type for the part of the operation during which the links and door sections swing, the length of the links and the distance of their connections with the upper door section from the door posts, must be taken into consideration as well as the weights of the door sections. Heretofore it has been necessary to make a weight diagram for each installation to determine the distance of the lower link pins from the door posts and to determine the center of gravity of the door sections in all of their positions. By this tedious process a distance may be found which with a given counterweight will cause the door sections to stand in any of their operative positions.

With this distance established the determination of the length of the links and the horizontal position of their connections with the edges of the upper door section become matters requiring another graphic diagram which sometimes upsets the factor found by the first mentioned diagram. After these matters have been computed, it often happens that changes must be made in these dimensions at the point of erection, and therefore inconveniently to compensate for variations in door weights and dimensions supposedly known. Therefore it is decidedly advantageous to have provision made for making such adjustment on the field. By making the links adjustable in length it is

also possible to carry doors in stock ready for quick delivery. Such links vary in some instances as much as three feet in length.

The distance of the lower link pins from the door posts also has to be changed on the field in many cases and so provision is made according to this invention for making this distance adjustable.

In Figs. 1 and 2, the links are shown as made of two parts 21 and 22 with holes 25 drilled in them, by which they may be connected by bolts or rivets 26 after the distance between their pivoted ends has been determined, or temporarily in different positions for the purpose of experimentally finding the desired length.

The link plate 23 is bolted to the edges of the upper door section as at 27. The link pin 40 projects from a flanged member 41 which is slideable within a larger circle 42 in plate 23. Its position therein may be adjusted radially in every direction by means of set screws 43.

It may be seen that with these expedients both the length of the links and the distance of the lower link pins from the door posts is made adjustable.

Another way of making the links adjustable in length is shown in Fig. 3 in which the part 22^A telescopes into the part 21^A and is held against longitudinal movement therein by set screws 28.

Another way of constructing the links so that they will be adjustable in length is shown in Fig. 4, in which the parts 21^B and 22^B are provided near their adjacent ends with right and left hand screw threads which fit into a rotatable adjuster 29. This arrangement provides for comparatively short adjustments.

The device shown in Fig. 5 is a turn buckle comprising right and left hand threaded eye-bolts 50 and 51 fitted into a shackle 52. An arrangement of this kind can be used with chain links or other forms of suspension links which are always under tension, as is the case in some of the doors of this type.

The link pin plate shown in Fig. 7 is designated by the numeral 45. 46 is the pin which projects therefrom. This plate is affixed to the edge of the door by a bolt 47 about which it can swing to vary the distance of the pin 46 from the door post and after the proper distance has been determined it can be affixed to the door section by another bolt through a hole 48 in the plate 45.

In Fig. 8 the link pin 55 projects eccentrically from a circular member 56 rotatably supported in a plate 57 affixed to the door section 20 by bolts 58. A set screw 59 is provided which passes through a threaded aperture in the plate 57 into engagement with the member 56 in order to hold it

against rotation after its proper position has been determined.

I have illustrated and described several modifications of construction in order to show that this invention is not limited to any specific form or detail of construction, and in fact I intend no limitations other than those imposed by the appended claims. It is not necessary that the doors stand vertically when closed or that the lower edges of the door sections move vertically. These edges have an up and down movement, however, and the section or sections are counterbalanced in some way either by the counterweight shown or an equivalent device.

What I claim is:

1. The combination with a door section, a counterbalance therefor, a hoisting element operatively connected between the lower edge of the door and the counterbalance, and means for guiding the lower edge of the door section in a direction other than horizontal, of adjustable links pivoted to points above the door section and to the sides of the door section intermediate the upper and lower edges thereof, and means for adjusting the length of said links.

2. The combination with a door section, a counterbalance therefor, a hoisting element operatively connected between the lower edge of the door and the counterbalance, and means for guiding the lower edge of the door section in a direction other than horizontal, of adjustable link supports above the door section, and adjustable links hung from said supports and pivoted to the sides of the door section intermediate the upper and lower edges thereof.

3. The combination with a door section, a counterbalance therefor, a hoisting element operatively connected between the lower edge of the door and the counterbalance, and means for guiding the lower edge of the door section in a direction other than horizontal, of adjustable pivots on the sides of the door section intermediate the upper and lower edges thereof, and links pivoted to points above the door section and connected with said adjustable pivots.

4. The combination with a door section, a counterbalance therefor, a hoisting element operatively connected between the lower edge of the door and the counterbalance, and means for guiding the lower edge of the door section in a direction other than horizontal, of adjustable pivots on the sides of the door section intermediate the upper and lower edges thereof, and adjustable links pivoted to points above the door section and connected with said adjustable pivots.

5. The combination with a door section, a counterbalance therefor, a hoisting element operatively connected between the lower edge of the door and the counterbalance, and means for guiding the lower edge

of the door section in a direction other than horizontal, of adjustable link supports above the door section, adjustable pivots on the sides of the door section intermediate the upper and lower edges thereof, and adjustable links between the link supports and said pivots.

6. The combination with a door comprising an upper section and a lower section, a counterbalance therefor, a hoisting element operatively connected between the lower door section and the counterbalance, means for guiding the lower door section in a direction other than horizontal, means for guiding the lower door section upwardly in relation to the upper door section, and means for limiting the relative movement of the door sections and thereafter causing parts of both sections to move upwardly together, of adjustable links pivoted to points above the door sections and to the sides of the upper door section intermediate its upper and lower edges.

7. The combination with a door comprising an upper section and a lower section, a counterbalance therefor, a hoisting element operatively connected between the lower door section and the counterbalance, means for guiding the lower door section in a direction other than horizontal, means for guiding the lower door section upwardly in relation to the upper door section, and means for limiting the relative movement of the door sections and thereafter causing parts of both sections to move upwardly together, of adjustable link supports above the door sections, and adjustable links hung from said supports and pivoted to the sides of the upper door section intermediate the upper and lower edges thereof.

8. The combination with a door comprising an upper section and a lower section, a counterbalance therefor, a hoisting element operatively connected between the lower door section and the counterbalance, means for guiding the lower door section in a direction other than horizontal, means for guiding the lower door section upwardly in relation to the upper door section, and means for limiting the relative movement of the door sections and thereafter causing parts of both sections to move upwardly together, of adjustable pivots on the sides of the upper door section intermediate the upper and lower edges thereof, and links pivoted to points above the door sections and connected with said adjustable pivots.

9. The combination with a door comprising an upper section and a lower section, a counterbalance therefor, a hoisting element operatively connected between the lower door section and the counterbalance, means for guiding the lower door section in a direction other than horizontal, means for guiding the lower door section upwardly in relation to the upper door section, and means for limiting the relative movement of the door sections and thereafter causing parts of both sections to move upwardly together, of adjustable links between the link supports and said pivots.

- tion to the upper door section, and means for limiting the relative movement of the door sections and thereafter causing parts of both sections to move upwardly together, 5 of adjustable pivots on the sides of the upper door section intermediate the upper and lower edges thereof, and adjustable links pivoted to points above the door sections and connected with said adjustable pivots.
10. 10. The combination with a door comprising an upper section and a lower section, a counterbalance therefor, a hoisting element operatively connected between the lower door section and the counterbalance, means 15 for guiding the lower door section in a direction other than horizontal, means for guid-

ing the lower door section upwardly in relation to the upper door section, and means for limiting the relative movement of the door sections and thereafter causing parts 20 of both sections to move upwardly together, of adjustable link supports above the door sections, adjustable pivots on the sides of the upper door section intermediate the upper and lower edges thereof, and adjustable 25 links between the link supports and said pivots.

In witness whereof, I have hereunto set my hand this 30th day of April, 1920.

JOHN EDWARD OGDEN.

Witness:

I. B. MOORE.
